A. O. RINGQUIST

REVERSIBLE WRENCH

Filed April 27, 1923

Inventor:
A.O. Ringquist

UNITED STATES PATENT OFFICE.

ALVIN O. RINGQUIST, OF FITCHBURG, MASSACHUSETTS.

REVERSIBLE WRENCH.

Application filed April 27, 1923. Serial No. 635,139.

To all whom it may concern:

Be it known that I, ALVIN O. RINGQUIST, a citizen of the United States, residing at Fitchburg, in the county of Worcester and 5 State of Massachusetts, have invented a new and useful Reversible Wrench, of which the following is a specification.

This invention relates to a wrench adapted for convenient progressive operation in 10 either direction and particularly designed for operations in relatively inaccessible places, such as the removal of nuts from connecting rod bolts in certain automobile engines.

15 It is the object of my invention to provide a wrench in which the head may be progressively advanced in either direction by intermittent, repeated movements of the handle and in which the head may be turned in 20 either direction as desired without adjustment or resetting of any part of the mechanism.

To the attainment of this object, I have provided a wrench having very few and simple parts and which may be cheaply manufactured and easily assembled.

25 My invention further relates to arrangements and combinations of parts which will be hereinafter described and more particularly pointed out in the appended claim.

A preferred form of the invention is shown in the drawings in which—

Fig. 1 is a side elevation of the wrench with the operating parts shown in section; 35 Figs. 2 and 3 are elevations of the opposite ends of the wrench head; and

Fig. 4 is a side elevation of the wrench.

Referring to the drawings, I have shown a 40 reversible wrench comprising a handle 10, a base or body 11 and a head 12 mounted for free rotation relative to the base 11. The handle 10 is formed with an offset construction, to render the wrench better adapted for particularly inaccessible places. A stud 13 is mounted in the base 11 and may be 45 formed integral therewith. The stud 13 is provided with a groove or recess 14 and with an end flange 15.

The wrench head 12 is loosely pivoted 50 upon the stud 13 and is held from displacement by a pin 16 projecting into the groove 14. The pin, however, is of much less di-

ameter than the width of the groove and permits a limited sliding movement of the head 12 on the stud 13.

55 Clutch teeth 17 and 18 are formed on the adjacent faces of the base 11 and head 12 and these teeth in the preferred form are of the rectangular or square faced type indicated in Fig. 4.

60 A spring 19 surrounds the stud 13 and engages a shoulder 20 of the head 12, the spring being disposed in suitable recesses in the parts 11 and 12. The spring 19 acts to yieldingly separate the teeth 17 and 18, so 65 that the head 12 is normally free to turn on the stud 13.

66 A hole 21 is formed in the head 12 opposite the pin 16 and a corresponding hole is formed in the stud 13 so that a pin or wire 70 may be inserted to drive out the pin 16, if it is desired to separate the parts. The outer end of the head 12 is formed to fit any desired size or style of nut or bolt head.

75 In using my improved wrench, the spring 19 normally holds the parts separated, so that the handle may be moved freely relatively to the head. The handle being thus freely swung to one extreme or the other of its path of movement, pressure is applied to 80 overcome the spring 19 and cause the teeth 17 and 18 to engage. The handle can then be swung in the opposite direction to move the head 12 angularly for a desired angular distance. When pressure on the handle is 85 released, the parts will immediately separate, freeing the handle for the return movement.

It thus appears that the wrench may be 90 made ready for turning a nut in either direction by simply placing the parts in the desired relation and pressing the base 11 against the head 12. My improved wrench is extremely simple in construction but is nevertheless fully adapted for the purposes 95 described and contains no delicate parts or fine adjustments which would be liable to breakage or displacement.

Having thus described my invention and the advantages thereof, I do not wish to be 100 limited to the details herein disclosed otherwise than as set forth in the claim, but what I claim is:—

A reversible wrench comprising a handle,

a body fixed thereto, a stud fixed relatively to said body and handle, said stud, body and handle forming a rigid unit, a head formed with a nut socket at one end and a cylindrical axial opening at the other end to receive said stud, holding means on said head co-operating with said stud to form a lost

motion connection between the parts, and means to normally yieldingly separate said parts, said body and head provided with co-¹⁰ operating clutch teeth.

In testimony whereof I have hereunto affixed my signature.

ALVIN O. RINGQUIST.
